COLOR INTENSITY CONTROL DEVICE FOR
INK SUPPLY MECHANISM FOR PRINTING
PRESSESFrederick M. Bender, White Plains, N. Y., assignor
to Speedy Gravure Corporation, New York,
N. Y., a corporation of New York

Application September 9, 1937, Serial No. 163,021

7 Claims. (Cl. 137—78)

This invention relates to a color intensity control device, and more particularly to a mechanism whereby the intensity of color of the inks fed to printing presses may be controlled within close limits.

In order to obtain a finished product of high quality in the color printing art, great care must be exercised to insure that the intensity of color of the inks used remains constant during the printing process. Inasmuch as the intensity of color of the inks varies during the operation, either additional ink or solvent must be added to restore the ink to the exact color intensity desired. This intensity of color heretofore has been usually determined by visual observation alone, and since the human eye is not sensitive to slight variations in color intensity, and is variably sensitive to any variations, the method is generally unsatisfactory.

An object of my invention is to provide a greatly improved device by means of which slight changes in the intensity of color of the ink can be instantly detected and corrected.

A further object of the invention is to provide a device of the above character in which the correction of the intensity of color of the ink is made automatically so that the color intensity of the ink can be maintained constant over long periods of operation.

The invention is attained by directing rays of light through a transparent chamber in which the colored ink flows. The light so transmitted is passed through a complementary color filter with the result that changes in the intensity of color of the ink appear as changes in the intensity of the light emanating from the color filter. By comparing the filtered light with light of a standard intensity, changes in color intensity of the ink may be instantly detected and corrected, or if desired, the beam of filtered light may be made to maintain a constant intensity of color of ink automatically.

Additional objects will be readily apparent from the following detailed description and from the accompanying drawing, wherein

Figure 1 is a schematic diagram of a control device constructed in accordance with this invention;

Figure 2 is a diagram illustrating the component parts of the system by means of which ink may be supplied to a printing press in accordance with the present invention.

Referring to Figure 1, the comparison device is designated by the number 5 and comprises a lamp 6 and a chamber 7 through which the ink

supply to the fountain flows. The sides 8 and 9 of the chamber 7 are of a transparent material in order that light from the lamp 6 may be transmitted through the ink stream into a closed cylinder 11. At the open end of the cylinder 11 there is secured a translucent apertured disc 12, the aperture being covered by a light filter 13 which is complementary to the color of the ink flowing in the transparent chamber 7. With this construction any change in the intensity of color of the ink supply results in a variation in the intensity of the light beam emanating from the filter 13.

A circular reflector 10 is adapted to fit snugly against the chamber 7, and is formed with a circular aperture in which the cylinder 11 is received. Light from a lamp 6' impinges on the surface of the reflector 10 and is reflected to the translucent disc 12 which is so constructed that light passing through it is of the same intensity as light passing through the ink in the chamber 7 when the color intensity of the ink is correct. In this fashion, the disc 12 constitutes a standard of comparison against which the intensity of the light passing through the filter 13 can be checked.

If the ink in the chamber 7 becomes too light in color, the intensity of the light from the filter 13 will increase relative to the standard, so that a central region of relatively high intensity is observed against an outer region of lesser intensity. While the human eye is not sensitive to slight changes in color intensities, it is quite sensitive to slight variations in light intensity. This device, therefore, can be used with a high degree of effectiveness to visually indicate slight variations in the intensity of colors of inks. The variations in color can then be readily corrected by manually adding either more ink or an ink solvent.

If it is desired to correct the variations in the color intensity of the ink automatically, it may be done by passing the beam of light from the filter 13 through a lens 14. The beam is focused on the photo-sensitive cell 15, which is connected through a wire 16 to the grid of a thyratron tube 17 of the type known as a 112A thyratron tube. The other side of the photo-sensitive cell 15 is connected to the filament of the tube 17 through a wire 18 and two resistors 19 and 20. In a typical circuit the resistor 19 has a value of 6000 ohms, while resistor 20 is of 600 ohms.

The changes in the current of the photo-sensitive tube appear as voltage variations developed in a resistor 21, which is connected in a

circuit 22 between the grid of the thyratron tube 17 and a variable point of the resistor 20. The resistor 21 may have a value of about 5 megohms.

The filament circuit of the tube 17 includes the resistors 23 and 24 which are in the wire 25 in series with the filament 27. Resistor 24 has a value in the neighborhood of 500 ohms while resistor 23 is of 100 ohms.

Voltage is supplied to the circuit of the thyratron tube from a separate circuit, including a power transformer 26 in the primary circuit of which is a switch 27. The two extreme ends of the secondary winding of the transformer 26 are connected by means of the wires 35 and 36 to one of the standard types of voltage regulator tubes 39 by means of which a constant alternating current voltage is maintained across the wires 40 and 41. From the wires 40 and 41 this constant voltage is fed to the photo-sensitive tube circuit, where it is impressed across the resistors 19 and 42 in series. In this fashion an alternating current voltage of constant magnitude is available for the polarization of the photo-sensitive tube 15 and the energization of the filament and plate circuits of the tube 17.

The plate circuit of the tube 17 includes a wire 43, one of the windings of a polarized relay 44, a variable resistor 45 and the wire 40. A condenser 46 approximately 1 microfarad in value is shunted from the wire 43 to the wire 25 in the filament circuit. The polarizing winding of the relay 44 is connected through the wire 48 to an extremity 49 of the resistor 42, while a second wire 47 is connected to a variable point 50 on the resistor 42.

By changing the position of the variable point 50, the voltage impressed on the polarizing winding of the relay 44 may be varied over a considerable range. In this manner it is possible to set up in the relay core a magnetomotive force of the required magnitude and direction to exactly balance out the magnetomotive force due to the current flowing in the main winding of the relay 44, which is in series with the plate circuit of the tube 17. In this balanced state, the permanently magnetized armature 51 of the relay 44 is maintained in an intermediate position between two sets of contacts, due to the compression of the spring 52.

As the ink supply becomes darker in color intensity, the photo-electric current decreases so that the plate current in the tube 17 is correspondingly reduced. The magnetomotive force due to the polarizing winding then dominates, and forces the armature 51 downwardly to engage contacts 53 and 54. This closes a circuit including a source of voltage and a wire 55 to which a relay 56 is connected. The relay 56 is thus energized so that its armature 57 is raised to engage contacts 58 and 59. A circuit is closed thereby through a source of voltage, a wire 60, a second wire 61 to which a switch 62 is connected, and a reversible motor 63 which is thus placed in operation. The shaft of the reversible motor 63 is connected to the stem of the gate valve 64 which controls the flow of solvent to the ink supply. Thus the closure of the upper contacts of the relay 57 acts to operate the motor and open the valve 64, thereby adding solvent to the ink mixture, and causing it to become lighter in color intensity. The switch 62 acts to stop the motor when the valve 64 is completely opened as will be described later.

When the intensity of color of the ink has become normal, the armature 51 of the relay 44

again assumes its intermediate position breaking the contacts 53 and 54 and thus de-energizing the relay 56. The armature 57 of the relay 56 drops and engages contacts 65 and 66, thus closing a circuit including the wire 60, a wire 67 to which a switch 68 is connected, and a second connection of the motor 63. With the new connection, the motor 63 will run in a reverse direction, thus closing the valve 64 and stopping the flow of solvent into the ink supply. The switch 68 is provided to stop the motor as soon as the valve 64 is completely closed, and is operated by the valve stem as will be described later.

If now the intensity of the color of the ink becomes too light, the magnetomotive force due to the increased plate current flowing through the main winding of the relay 44 dominates, so that its armature 51 is forced upwardly against the tension of the spring 52 to engage contacts 53' and 54'. A circuit is closed thereby including a wire 55', a relay 56' and a source of voltage by means of which the relay 56' is energized. The armature 51' of the relay 56' then rises engaging contacts 58' and 59', thereby closing a circuit including a source of voltage, the wires 60' and 61', a switch 62' and a reversible motor 63'. The motor 63' is then put into operation opening a valve 64' which controls the flow of ink to the ink supply. When the valve 64' is completely opened, the motor is shut off by means of the switch 62' as will be described later.

After sufficient ink has been added to the ink supply to bring it back to its normal color intensity, the armature 51 once more resumes its intermediate position thus de-energizing the relay 56'. Its armature 51' then drops, breaking the contacts 58' and 59' and engaging contacts 65' and 66'. A circuit is closed thereby including a source of voltage, wires 60' and 67', a switch 68' and a second connection on the motor 63'. With this second connection the motor 63' is caused to rotate in the reverse direction, so that the valve 64' is closed and ink is no longer fed to the ink supply. When the valve 64' is completely closed, the motor 63' is shut off by means of the switch 62' as will be shown later.

As indicated in Figure 2 the ink system comprises an ink storage tank 69 connected to the supply tank 72 through a pipe 71 in which there is a valve 64' operated by the reversing motor 63' not shown. A solvent storage tank 73 is likewise connected to the supply tank 72 by means of a pipe 74 in which there is connected the motor driven valve 64. The mixture of ink and solvent in the supply tank 72 is circulated by means of a pump 75 through a pipe 76, the ink fountain 77 and back to the supply tank 72 through a tube 78. The device 5 above described is connected in the pipe 76 where it registers any changes in the intensity of color of the ink and brings the color intensity back to normal by automatically operating either of the valves 64 or 64'.

Reference has been made above to a mechanism by means of which the motors 63 and 63' may be shut down when the valves 64 or 64' respectively are completely opened or completely closed. It comprises the reversible motor 63 and its shaft 78 on which a pin 79 is formed. The pin 79 is adapted to be received slidably in a spiral groove 80 formed in a coupling member 81 which is splined to the stem 83 of the valve 64. On the coupling member 81 is secured a flange 82 which is adapted to engage the elements of the switches 62 and 68 in the wires 61 and 67 respectively. When the valve 64 is opened, its

spindle 81 moves axially outward, moving the flange 82 in a corresponding manner. The switch 62 is so disposed that when the valve 64 is completely opened the flange 82 engages the contact 85 of the switch 62, thus opening it and stopping the motor 63.

Conversely during the closure of the valve 64, its spindle 81 moves axially inward, and with it moves the flange 82. When the valve 64 is completely closed, the flange 82 engages the contact 84 of the switch 68, thus opening it and again stopping the motor 63. A similar mechanism is provided for the motor 63' and the valve 64'. In this fashion all possibility of motor burn-outs or damage to the valve which would ordinarily result on operation of the motor beyond the limits set by the valve stops is avoided.

The device instantaneously registers any changes in the color intensity of the ink fed to the ink fountain, and thereupon automatically causes either ink or solvent to be fed thereto for the purpose of preserving a desired color intensity of ink. As a result of this invention ink of constant color intensity may be readily obtained over long periods of operation, with a minimum of supervision.

It is evident that the mechanism herein disclosed is capable of considerable modification within the scope of the invention. For example, the control of the intensity of the ink color need not be effected by directing light through the transparent ink chamber, but may be accomplished through light reflection from the body of ink. In this case only one transparent wall is necessary in the ink chamber, and light may be supplied from a source in conjunction with an appropriate optical system. The light reflected from the body of the ink in the ink chamber then serves to indicate changes in the color intensity of the ink.

As a further modification, light of a complementary color may be directed through the ink, thus dispensing with the color intensity filter on the color control device.

Inasmuch as, in commercial printing operations, an ingredient known as "extender" is used as well as solvent to maintain a desired uniformity of tone strength, it is understood that this invention contemplates such use, and, if desired, the addition of the extender may be controlled as well as the solvent by means of this invention.

Since additional modifications are possible, it is to be understood that the above specification is presented only as descriptive of the invention, and the latter is to be in no way limited thereby save as defined in the appended claims.

I claim:

1. A color intensity control device in inking mechanisms for printing presses comprising an ink fountain, light means sensitive to variations of the color intensity of the ink supplied to the said ink fountain, a lens to focus the light from the said light means, a photo-sensitive cell responsive to the said focused light, a pipe to supply ink to the ink fountain, a second pipe to supply solvent to the ink fountain, a valve in each of the said pipes, a reversible electric motor on each of the said valves, circuits for each of the said motors, and means actuated by the said photo-sensitive cell to energize the said motor circuits.

2. A color intensity control device in inking mechanisms for printing presses comprising an ink fountain, light means sensitive to the color intensity of the ink supplied to the ink fountain,

5 a lens to focus the light from the said light means, a photo-sensitive cell responsive to variations of intensity of the said focused light, a pipe to supply ink to the said ink fountain, a second pipe to supply solvent to the said ink fountain, a valve in each of the said pipes, a reversible electric motor on each of the said valves, circuits for each of the said motors including the contacts of a relay, a circuit for each of the said motor relays including the contacts of a third relay, a circuit for the said last relay, and means actuated by the said photo-sensitive cell to energize the circuit of the last relay.

10 3. A color intensity control device in inking mechanisms for printing presses comprising an ink fountain, light means sensitive to variations of the color intensity of the ink supplied to the ink fountain, a lens to focus light from the said light means, a photo-sensitive cell responsive to variations of intensity of the said focused light, a pipe to supply ink to the said ink fountain, a second pipe to supply solvent to the said ink fountain, a valve in each of the said feed pipes, a reversible electric motor on each of the said valves, circuits for each of the said motors including the contacts of a relay, a circuit for each of the said motor relays including the contacts of a third polarized relay, a circuit for the said polarized relay including the plate of a thyratron tube, the said thyratron tube being actuated by the said photo-sensitive cell.

15 4. A control device in inking mechanisms for printing presses comprising an ink fountain, means sensitive to the intensity of the color of the ink supplied to the ink fountain, a pipe to supply ink to the ink fountain, a second pipe to supply solvent to the ink fountain, a valve in each of the said pipes, reversible electric motors connected to the respective valves to open and close the same, circuits for each of the said motors, means actuated by the motors to break the said circuits for the said motors when the valves are open or closed, means actuated by the means sensitive to the color intensity of the ink for energizing the said circuits.

20 5. A control device in inking mechanisms for printing presses comprising an ink fountain, light means sensitive to the intensity of the color of the ink supplied to the ink fountain, a lens to focus light from the said light means, a photo-sensitive cell responsive to variations of the intensity of the said focused light, a feed pipe to supply ink to the said ink fountain, a second pipe to supply solvent to the said ink fountain, a valve in each of the said pipes, reversible electric motors connected to the respective valves to open and close the same, circuits for the said motors, a plurality of switches in the said circuits to shut off the said motors, means associated with the said valves and actuated by said motors to operate the said switches when the valves are closed or open, and means actuated by the said photo-sensitive cell to energize the said circuits selectively to open and close said switches.

25 6. A method of controlling the color intensity of inks used in the inking systems of printing presses, which consists in directing a light beam to the ink to cause a first light beam to be emitted therefrom and directed to a desired viewing position, utilizing the characteristic color of the ink as a complementary color to cause the light at the viewing position to lack color but be of a discernible intensity, directing

a second light beam of standard intensity but of no characteristic color to the viewing position and adjacent the aforesaid light, viewing the first light and the second light of standard intensity, and controlling the supply of ink ingredients upon variation of such light intensity to maintain substantially equal intensities of the said first light beam and the standard light beam, whereby a desired intensity of color of the ink is maintained.

7. In a method of controlling the color intensity of ink used in inking systems of printing presses, the steps of directing light of pre-

determined intensity through the ink, passing the resulting rays through a filter of a color complementary to the desired color of the ink, the density of the filter being such that light free from the color of the ink and of discernible intensity is transmitted when the ink is of desired intensity of color, directing light of a standard intensity and neutral color adjacent said filtered light rays, and viewing the latter in comparison with the light rays of standard intensity to ascertain deviations of the color intensity from the chosen standard of intensity.

FREDERICK M. BENDER.
